UNITED STATES PATENT OFFICE.

DALLETH Z. MERCHANT, OF NORFOLK, VIRGINIA.

DESIGN FOR A SMOKING-PIPE.

No. 38,164.

Specification for Design.

Patented Aug. 14, 1906.

Application filed May 21, 1906. Serial No. 318,102. Term of patent 3½ years.

To all whom it may concern:

Be it known that I, DALLETH Z. MERCHANT, a citizen of the United States, residing at Norfolk, in the county of Norfolk and State of Virginia, have invented a new, original, and ornamental Design for a Smoking-Pipe, of which the following is a specification, reference being had to the accompanying drawings, in which—

Fig. 2 is a side elevation thereof, showing the design.

I claim—

The ornamental design for a smoking-pipe as shown.

DALLETH Z. MERCHANT.

Witnesses:

T. T. MASENGILL,

WALTER B. BURROW.
